Lacey Lacey, 1874, S.

UNITED STATES PATENT OFFICE.

JAMES DYKES, OF MARINETTE, WISCONSIN.

PORTABLE CRANE.

1,374,837.

Specification of Letters Patent. Patented Apr. 12, 1921.

Application filed December 26, 1919. Serial No. 347,342.

To all whom it may concern:

Be it known that I, JAMES DYKES, a citizen of the United States, residing at Marinette, in the county of Marinette and State 5 of Wisconsin, have invented certain new and useful Improvements in Portable Cranes, of which the following is a specification.

This invention relates to portable cranes 10 and more especially to a crane designed for employment on railways in loading flat and other similar cars, and the invention is designed more particularly as an improvement on the structure shown in my Patent 15 No. 1,213,603, issued January 23, 1917.

One of the objects of the present invention is to provide an improved means for securing the base of the crane upon the track over which the cars to be loaded are 20 to pass, the securing means being constructed to firmly and rigidly hold the base in place upon the track.

Another object of the invention is to provide an improved means for rotatably supporting the boom of the crane upon the mast.

In the accompanying drawings:

Figure 1 is a side elevation of the crane embodying the present invention, parts being shown in section;

Fig. 2 is a group perspective view illustrating the means provided for mounting the boom upon the mast;

Fig. 3 is a horizontal sectional view taken 35 in a plane below the boom;

Fig. 4 is a view partly in side elevation and partly in longitudinal section illustrating a modified form of base;

Fig. 5 is a top plan view of the base 40 shown in Fig. 4.

The base of the device is indicated in general by the numeral 1. This base is designed to support the mast of the crane, and the construction of the base and the means 45 provided for securing the mast in place thereon will presently be more specifically described.

The mast is indicated in general by the numeral 2 and upstands from the outer end 50 of the base and this mast is preferably of hollow form and interiorly is tapered from its upper to its lower end as indicated by the numeral 3, I having found that by thus constructing the mast the same will be better adapted to stand the strains to which

it is subjected in the loading and unloading operations.

The boom is indicated in general by the numeral 4 and the same comprises a T-beam disposed in inverted position the horizontal wings of this beam being indicated by the numeral 5 and the vertical wing by the numeral 6, the latter constituting a rail upon which are adapted to travel wheels 7 of a hanger 8 to which may be connected any suitable hoisting mechanism a portion of which is indicated by the numeral 9. In this manner the hoisting mechanism is of course arranged to be moved back and forth along the boom so that the load supported thereby may be suitably maneuvered in loading it onto and unloading it from the cars. In order to limit the outward travel of the hanger 8 upon the rail 6, the beam comprising the boom is provided at its 70 outer end with an upstanding abutment 10 as clearly shown in Fig. 1 of the drawings. For a short distance at the inner end of the boom, the wings 5 are cut away as indicated by the numeral 11 and angle members, indicated by the numeral 12, which project in parallel spaced relation from an annular head 13, are disposed to straddle the upstanding wing or rail 6 at the inner end of the boom and are both riveted, or otherwise secured thereto as indicated by the numeral 14. The horizontally disposed wings of these angle members 12 form in effect continuations of the inner ends of the wings 5 of the boom and the said wings of 80 the angle members and the wings of the boom are riveted or otherwise secured as indicated by the numeral 15 to the upper side of a bearing member which is indicated in general by the numeral 16. This bearing 90 member comprises a horizontally disposed head 17 and a depending longitudinally extending web 18 the function of which will be presently described. The angle members 12 serve of course as a means for securing the annular head 13 to the inner end of the boom, and this head is designed to encircle the upper end of the mast of the crane and to rotate about the same.

In order that the boom may be rotatably supported upon the mast through the medium of the annular head 13, a collar 19 is fitted onto the mast near its upper end and is held in place by means of a set screw 20 or any other means suitable for the purpose. 110

The head 13 is interiorly of a diameter greater than the external diameter of the mast and is disposed to surround the mast above the collar 19, resting at its lower side 5 upon the upper side of the said collar as clearly shown in Fig. 1 of the drawings. Bearing rollers 21 are disposed in an annular series within the space between the inner circumference of the head 13 and the 10 exterior surface of the mast 2 and serve to reduce the friction attending the rotation of the head about the mast. A retaining ring 22 is disposed within the upper portion of this space and serves to prevent upward displacement of the bearing rollers 21, downward displacement of the rollers being prevented by the collar 19 upon which the said rollers rest at their lower ends.

The inner end of the web 18 lies relatively 20 close to the exterior surface of the mast 2 and is formed with a series of sockets 23 in which are disposed bearing balls 24 which ride against the said exterior surface of the mast. The sockets 23 are preferably 25 in the nature of transverse substantially semi-circular notches and in order to retain the bearing balls 24 therein, a retaining member such as shown in Fig. 2 of the drawings and indicated in general by the 30 numeral 25, is provided. This retaining member is formed from an integral sheet metal blank which is bent to provide side portions 26 and a lower connecting portion 27, the member being disposed to straddle 35 the lower side of the web 18 at the inner end of the web and being secured in place by bolts or rivets 28. The side portions 26 of this member close the ends of the notches 23 and thus serve to prevent the 40 bearing balls 24 dropping from the said notches as stated.

Due to the construction above described, the boom is enabled to support a heavy load and yet be relatively free to swing angularly 45 about the mast, the bearing balls 24 engaging that side of the mast which receives the thrust of the member 16, and the roller bearings 21 riding against the opposite side of the mast. It will be noted by reference to 50 Fig. 1 of the drawings that the portion of the web 18 in which the sockets 23 are formed is in effect a projection from the inner end of the said web and provides a shoulder 29 which engages beneath the collar 19 and thus prevents upward displacement of 55 the bearing portion of the boom upon the mast.

The base of the device in that form illustrated in Figs. 1 to 4 inclusive, comprises a 60 relatively wide U-beam indicated by the numeral 30 which beam is disposed in position with its lateral wings 31 upstanding in vertical planes, its connecting web 32 resting upon the upper side of the head of the rail R 65 as shown in Figs. 1 and 3 of the drawings.

Legs 33 are secured at their upper ends to respective ones of the wings 31 and are inclined downwardly at such an angle that when the web of the beam is disposed upon the tread of the track rail, the lower ends of 70 the arm 33 will bear against the outer side of the web of the rail near the base flange thereof as illustrated in Fig. 1. In order to firmly support the outer end of the beam 30, a sill 34 may be employed and disposed 75 transversely of the ties of the track and parallel to the rail R and in position beneath the said end of the beam. In order to prevent the base lifting off the rail, clamp members 35 are provided and these members are 80 in the nature of yokes having portions 36 extending transversely of the upper side of the beam 30, and depending end portions or arms 37 which have inwardly directed terminals 38 which engage beneath the head of 85 the rail at the opposite sides thereof in the manner illustrated in Fig. 1. The beam 30 is formed in its web 32 with slots 39, and wedge keys 40 are driven into these slots and bear at their adjacent edges against holding members 39' each in the nature of a bar disposed against the under side of the beam with one end engaging the arms 37 of the 90 respective locking member and its opposite edge engaged by the respective wedge 40, 95 these bars being supported by means of arms 40' carried at their outer ends and having hooked upper terminals 40a which engage over the upper edges of the lateral wings 31 of the beam 30.

In supporting the mast 2 upon the beam 30, the beam at its end which is to support the said mast has its lateral wings 31 slit vertically and the beam is then bent along a line transversely of its web 32 to provide 105 an upstanding bracing portion 30' having side portions 31' comprising portions of the lateral wings 31 of the said beam. Diagonal braces 32' of angle or channel iron are riveted or otherwise secured at their lower and 110 upper ends respectively to the wings 31 and the side portions 31' and serve to brace the member 30' in upright position, rivets 33' being driven through the wings 31 and the 115 said side portions 31' where the latter overlap the former so as to further brace the parts. U-bolts 34' are disposed to straddle the lower end of the mast 2 and the ends of these bolts project through openings in the web of the upstanding bracing member 120 30' and have nuts 35' threaded thereon, the lower end of the mast being in this manner secured to the bracing member 30' and with its lower end resting upon the adjacent portion of the web 32 of the beam 30.

Figs. 5 and 6 of the drawings illustrate a modified form of base, the base in this form being designed especially for use where the crane is to be employed in lifting massive loads, and this base which is indi- 125 130

cated in general by the numeral 41, comprises a substantially U-shaped frame of channel-iron construction supporting at its bend a base 42 having a step bearing 43 to receive the lower end of the mast 2. The base is to be so disposed upon the sills 44 at opposite sides of the rail R that the web of the channel-iron from which the base is formed will rest upon the upper sides of the 10 sills. A cross beam 45 extends between the extremities of the side members of the frame 41 as shown in the said Figs. 5 and 6 and the depending wing of this cross beam is designed to engage against that one of the 15 sills 44 upon which the extremities of the said side portions of the frame rest as illustrated in Fig. 5 so as to prevent displacement of the frame with relation to the sill or vice versa.

20 In order that the frame 41 may be clamped to the rail R, a relatively fixed clamp member 46 is bolted or otherwise secured as at 47 to the under side of each of the said side members of the frame and is 25 provided with a downwardly extending portion 48 designed to engage beneath the head of the rail at one side thereof as shown in Fig. 5. A similarly formed clamp member 49 is provided with a downwardly 30 extending portion 50 which is designed to engage against the other side of the head of the rail, and bolts 51 are passed through this clamp member and through slots 52 formed in the web of the respective side 35 member of the frame, this connection permitting of longitudinal adjustment of the clamp member 49 with relation to the respective side member of the frame and consequently toward and away from the respective fixed clamp member 46. In order that the member 49 may be caused to bind firmly 40 against the rail prior to tightening of the bolts 51, the web of each side member of the frame is formed with a slot 53 and the 45 attaching portion of the clamp member 49 is formed with a similar slot 54. A bar or other implement 55 may be inserted within these slots and as the slots are initially out of exact registration and their opposite end 50 walls are relatively displaced, the bar or the like 55 may be manipulated so as to exert a leverage against one end wall of the slot 53 and the opposite end wall of the slot 54 so as to force the clamp member 49 in the direction of the rail for the purpose 55 stated.

Having thus described the invention, what is claimed as new is:

1. In a device of the class described, a 60 mast, a boom, a head carried at the inner end of the boom and rotatably fitting the mast, a collar upon the mast restraining the head from downward movement, a bearing member secured to and depending from the 65 head and the boom and riding against the

mast below the collar, the said bearing member forming a rigid connection between the head and the boom and having a seat in its portion which confronts the mast, and an anti-friction bearing element disposed with- 70 in the seat.

2. In a device of the class described, a mast, a boom, an annular head carried at the inner end of the boom and rotatably fitting the mast, a collar upon the mast supporting the head against downward movement, a bearing member carried by the boom and having a web one edge of which is located contiguous to the mast, the said edge portion of the web being formed with 75 a transverse recess, a bearing element seated in the recess and riding against the mast, and a retaining member having side portions, the said member being disposed to straddle the web with its side portions closing the opposite ends of the recess.

3. In a device of the class described, a mast, a boom, an annular head carried at the inner end of the boom and rotatably fitting the mast, a collar upon the mast supporting the head against downward movement, and a bearing member carried by the boom and riding against the mast below the collar and having a shoulder whereby to prevent upward displacement of the boom 95 upon the mast.

4. In a device of the class described, a base comprising a beam having a web and upstanding lateral wings, the beam being bent at one end to provide an upstanding 100 bracing member having a web and lateral wings overlapping the wings of the body of the beam and secured thereto, and a mast disposed to rest at its lower end upon the web of the body of the beam and at one side 105 against the web of the bracing member, and means securing the mast to the said bracing member.

5. In a device of the class described, a base comprising a beam having a web and 110 upstanding lateral wings, the beam being bent at one end to provide an upstanding bracing member having a web and lateral wings overlapping the wings of the body of the beam and secured thereto, and a mast 115 disposed to rest at its lower end upon the web of the body of the beam and at one side against the web of the bracing member, and means securing the mast to the said bracing member, the said means comprising 120 U-bolts straddling the lower portion of the mast and secured through the web of the said bracing member.

6. In a device of the class described, a base comprising a beam having a web and 125 upstanding lateral wings, the beam being bent at one end to provide an upstanding bracing member having a web and lateral wings overlapping the wings of the body of the beam and secured thereto, and a mast 130

- disposed to rest at its lower end upon the web of the body of the beam and at one side against the web of the bracing member, means securing the mast to the said bracing member, the said means comprising U-bolts straddling the lower portion of the mast and secured through the web of the said bracing member, and diagonal bracing members secured at their lower ends 10 to the wings of the body of the beam and at their upper ends to the wings of the bracing member.
7. In a device of the class described, a base comprising a beam having a web and upstanding lateral wings, anchoring members comprising yokes disposed to straddle the said beam transversely and having rail engaging lower ends, holding members comprising bars engageable with the anchoring members and slidably supported upon the

beam, and wedges to be driven through the web of the said beam to urge the holding members into engagement with the anchoring members.

8. In a device of the class described, a 25 base comprising a beam having a web and upstanding lateral wings, anchoring members comprising yokes disposed to straddle the said beam transversely and having rail comprising bars engageable with the anchoring members and provided with hooked terminals slidably supported upon the beam, and wedges to be driven through the web 30 of the said beam to urge the holding members into engagement with the anchoring members.

In testimony whereof I affix my signature.

JAMES DYKES. [L. s.]
